UNITED STATES PATENT OFFICE.

JOHN McC. WATSON, OF PITTSBURG, PENNSYLVANIA.

DESIGN FOR A SPICE-BOTTLE.

SPECIFICATION forming part of Design No. 12,908, dated April 25, 1882.

Application filed March 20, 1882. Term of patent 3½ years.

To all whom it may concern:

Be it known that I, JOHN McC. WATSON, of Pittsburg, in the county of Allegheny and State of Pennsylvania, have invented a new and useful Improvement in Design for Spice-Bottle; and I do hereby declare the following to be a full, clear, and exact description thereof, reference being had to the accompanying drawings, forming a part of this specification, in

10 which—

Figure 1 is a side elevation, and Fig. 2 is a vertical section, of a spice-bottle made after my improved design.

15 Like letters of reference indicate like parts in each.

Around the lower part of the bottle is formed a collar or ring, *a*, being larger in circumference than the bottom of the bottle. Above the ring or collar *a* is another ring or collar, *b*, 20 which is smaller in width and in circumference than the ring *a*. Above the ring or collar *b* is a ring or collar, *c*, which is smaller in width and circumference than the ring *b*. These rings join each other—that is, one is directly

above the other, without any space intervening. 25 From the ring *c* the bottle tapers to the shoulder *d*, which is preferably at a point three-fourths of the height of the bottle. From the shoulder *d* the bottle tapers in a concave line to the ring *e*, above which is the mouth of the 30 bottle, which is either of screw form for the application of a screw-cap, *f*, or of lip form for the reception of a stopper.

I propose to apply this design to spice and 35 caster bottles generally, and also to other articles of table-ware, such as salts, and pepper-dredges not used in a caster-stand.

My design is plain and handsome.

What I claim as my invention, and desire 40 to secure by Letters Patent, is—

The design for caster-bottles, substantially as described and shown.

In testimony whereof I have hereunto set my hand this 17th day of March, A. D. 1882.

JOHN McC. WATSON.
